UNITED STATES PATENT OFFICE.

ROBERT E. DORTON, OF MINNEAPOLIS, MINNESOTA, AND HARRY L. EARLE, OF NEW YORK, N. Y., ASSIGNEES TO ROBERT J. ANDERSON, OF MINNEAPOLIS, MINNESOTA.

BAND-CUTTING AND FEEDING MECHANISM.

SPECIFICATION forming part of Letters Patent No. 439,489, dated October 28, 1890.

Application filed December 12, 1889. Serial No. 333,458. (No model.)

To all whom it may concern:

Be it known that we, ROBERT E. DORTON and HARRY L. EARLE, citizens of the United States, residing, respectively, at Minneapolis, in the county of Hennepin and State of Minnesota, and at the city of New York, in the county and State of New York, have invented certain new and useful Improvements in Band-Cutting and Feeding Mechanism, of which the following is a specification.

Our invention relates to that class of mechanism designed to receive bound bundles of grain, cut their bands, and deliver the grain into a thrashing-machine.

The improvements consist in the manner of hinging the parts to admit of their being folded on the thrasher, in side conveyers arranged out of line with each other and delivering upon the intermediate main conveyer, in side conveyers arranged to deliver alternately, in various improvements in the band-cutting devices, and in various details of the conveyers, all as hereinafter explained and described in detail.

In the accompanying drawings, Figure 1 is a top plan view of our attachment applied to a thrasher. Fig. 2 is an end elevation of the same, with a portion in section, on the line $x-x$ of Fig. 1. Fig. 3 is a vertical cross-section on the line $y-y$ of Fig. 1. Fig. 4 is a vertical cross-section of one of the band-cutters. Fig. 5 is a top plan view of one end of the cutter, showing the manner in which it is supported. Fig. 6 is a side view of one of the cutter-supporting arms. Fig. 7 is a detail view of one of the pickers. Fig. 8 is a side view showing the manner in which our mechanism is attached and driven, the relative positions of the side frames being indicated in dotted lines. Figs. 9 and 10 are views showing the pickers or spreaders in different forms.

A represents the main frame of my attachment, hinged to the receiving end of the thrasher or separator at a , and sustained by hinged braces a' , so that it may be folded upon the machine when not in use. This frame A contains the endless constantly-driven apron B, passing around rolls $b b'$ at

its ends and serving to deliver the loose grain to the thrashing-cylinder.

To opposite sides of the frame A, at right angles to the length of the feed-apron and at different points in its length, we hinge the secondary frames C C', each provided with mechanism for cutting the grain-bands, opening or spreading the sheaves, and delivering the loose grain to the feed-apron B, as hereinafter described in detail. The location of the frames C C' at different points in the length of the main conveyer-apron and on opposite sides thereof prevents the grain from both frames from being deposited on the apron at the same point, in which case there would be a liability of the thrashing-cylinder becoming clogged. The machine is balanced by the frames being on opposite sides.

The hinged connections between the main and side frames are preferably made, as shown, by providing the frame A at its front with a rigid arched frame a^2 , to opposite sides of which are bolted brackets a^3 . Similar brackets are attached to the opposite sides of the frame A, all of these brackets being formed to receive tubular journals a^4 , bolted to the side frames.

By hinging the side conveyers to the main conveyer that they may close upward and inward toward each other, and also hinging the main conveyer so that it may fold upward toward the thrasher, carrying with it the folded side conveyers, I am enabled to close the parts into compact shape and to place their weight in such relation to the machine that it may be safely and readily transported on the road and carried through gates and other restricted openings.

We will now describe the feeding, cutting, and spreading mechanisms of the frame C, which are in all respects duplicates of those on frames C', so that the description of one may be considered a description of the other, except that in the one case the parts move to the right toward the feed-apron, while in the other they move to the left. The bound sheaves, laid upon the outer end of the frame, which has a top or table, are carried inward

thereover by parallel chains or belts E, traveling lengthwise of the frame around sustaining pulleys or rollers $e e'$, and provided with teeth e^2 to engage and positively move the grain. The 5 chains travel forward over the upper surface of the frame and sink through slots therein just before reaching its inner end, so that the grain is stripped from the teeth and prevented from being carried back beneath the table. The 10 end of the table is extended inward and curved downward, so that the grain is delivered upon the feed-apron below.

The cutting of the bands is effected during their passage over the table by two over- 15 head serrated reciprocating knives F F, similar to the knives of mowing and reaping machines, arranged side by side and moving in reverse directions, so that they operate with a shearing action and without tendency to 20 move the grain endwise. The knives (shown clearly in Figs. 1, 2, and 3) extend crosswise of the table and are inclined or tipped side- 25 wise, so that the ends of the cutting-points are presented toward the incoming grain. In practice it has been found that the cutters thus inclined act with more certainty and ease than those arranged vertically, since the carrying-chains act to carry the grain and band directly against the knives and between 30 their points.

In order that the knives may act with certainty on both large and small sheaves, and that the large sheaves may not choke or retard the action of the parts, we mount the 35 entire cutting mechanism on the free end of two arms f f, pivoted at f' to standards on the frame. The arms stand normally in an inclined position, with their elevated pivoted ends toward the incoming grain, on which 40 they float, thus raising and lowering the cutter automatically in accordance with the size of the sheaves passing thereunder. Each knife consists, like a mower-knife, of a series of small triangular blades f², which are riveted to an angle-iron bar f³. The two knives are sustained by and between two parallel angle-iron bars f⁴, which are connected by cross-plate f⁵ and attached at the ends to necks f⁶, secured by set-screws f⁷ in blocks f⁸, 45 which are in turn sustained by transverse pivots in the ends of the arms f f. This arrangement permits the two ends of the cutter to rise and fall independently. The knives are actuated by pitmen f⁹, attached to a double 50 crank-shaft f¹⁰, seated horizontally in a bearing or standard f¹¹, rising rigidly from the side of frame C.

In order to secure a constant and uniform delivery of the grain to the feed-apron, the 55 sheaves must be opened, or, in other words, the grain spread out before delivery to the apron. For this purpose we provide a series of pickers or spreaders H. They may be mounted at the middle on a crank-shaft h, and guided at the heel ends by vibrating levers h', as in Fig. 9, so that when the shaft is turned the fingers will be thrust upward

through the grain-table and carried forward toward the delivery end with short rapid strokes, so as to spread the grain and carry 70 the same over the edge of the table to the feed-apron below. Each tooth after completing its advance is withdrawn and retreats beneath the table preparatory to its next stroke. The delivery end of the table is curved downward and slotted, as shown, in order to strip 75 the grain from the picker-teeth and prevent it from being carried backward under the table.

The picker-teeth or spreader-teeth, instead 80 of being operated as above described, may be carried by cranks and guided at the heel by a fixed cam h²⁰, as in Fig. 7; or the pickers may be of sector-shape, mounted to vibrate on a shaft h⁴, under the influence of pitmen h⁵ and 85 cranks h⁶, as in Fig. 10. We prefer, however, pickers having the circulatory movement first above described.

In order to secure delivery of the grain to the feed-apron B from the two sides alternately, we propose to provide the conveyers E with teeth for a portion of their length only, and to arrange the group of teeth on one series of chains in such relation to the teeth of the chains on the opposite side of the machine 95 that they will come into action alternately—that is to say, so that the teeth of the right-hand chains will act upon the grain, while the teeth of the left-hand chains are inactive, and vice versa.

The operative parts above described are driven as follows: The main driving-shaft K, carrying the driving-pulley L and the front roll of apron B, is mounted horizontally across the outer end of the frame A and provided 105 with beveled pinions k, engaging pinions k', connected through clutches k¹⁶ to vertical sprocket-wheels k². From these wheels chains k³ extend around the respective wheels k⁴ k⁴, fixed on the ends of shafts k⁵. These shafts 110 are extended horizontally across the inner ends of the side frames and seated in the tubular boxes, before referred to as forming part of the hinges between the main and side frames. By thus arranging the shafts k⁵ concentric with the hinges the folding of the 115 side frames, as before referred to, is permitted without disturbance of the driving-connections. Each of the shafts k⁵ carries a sprocket-wheel k⁶, connected by chain k⁷ to a 120 sprocket-wheel k⁸ on the adjacent shaft k¹⁹. Each of the shafts k¹⁹ carries at the inner end a beveled pinion k⁹, engaging pinion k¹⁰ on a vertical shaft, which is in turn connected by pinions k¹² k¹³ to the crank-shaft, which 125 drives the cutters. The shafts k⁵ carry the pulleys for driving the feed-chains.

Having thus described our invention, what we claim is—

1. In combination with a thrasher, a conveyor-sustaining frame hinged to its end to fold upward and inward toward the thrasher, two lateral conveyer-frames hinged to the main conveyer to fold upward and inward

toward each other, and supports, substantially as shown, to sustain said hinged frames in operative positions, whereby the three conveyers are permitted to fold into compact 5 form over the thrasher for transportation.

2. In a feeder for a thrashing-machine, a conveyer to deliver the grain to the thrasher, in combination with two lateral conveyers delivering to the first at different points in its 10 length.

3. In combination with the intermediate conveyer feeding to the thrasher, the two conveyers delivering to the first from opposite sides and at different points in its length.

15 4. In combination with a thrasher and a conveyer delivering with a constant motion thereto, a lateral conveyer and chains feeding to the first conveyer and toothed for a part 20 of their length only, whereby the grain is delivered to the main conveyer intermittently, and thus distributed thereon to cause a regular feed to the thrasher.

25 5. In combination with the conveyer-apron B and intermediate connecting-gear, the two series of conveyer chains or belts located on opposite sides of and delivering to the apron, said chains or belts provided with teeth relatively arranged to cause the delivery of grain to the two sides of the apron alternately.

30 6. In a band-cutter and feeder, the reciprocating cutter, the guide-bars to sustain the same, the bearing-blocks at the ends of said bars, and the sustaining-arms pivotally connected to said blocks, whereby the ends of

the cutter are permitted to rise and fall independently. 35

7. In combination with a thrasher, a main conveyer delivering thereto, the elevated secondary conveyer feeding laterally to the main conveyer, and the circulating pickers arranged to rise through the inner end of the secondary conveyer, as described, whereby the grain is separated and thrown forward from the secondary to the main conveyer. 40

8. In combination with the grain-sustaining table having the downwardly-curved and slotted end, the conveyer-chains moving over the table and vanishing therethrough before reaching the delivery end, the pickers arranged to sweep through the slotted end of 45 50 the table, as shown, and a cutter to sever the bands in advance of the pickers.
